(57) **CLAIM**

The ornamental design for reflective scarf, as shown and described.

DESCRIPTION

FIG. 1 is a perspective view of the reflective scarf of the present invention.

FIG. 2 is an enlarged cross-sectional view taken along Line 2-2 of FIG. 1.

FIG. 3A is an enlarged left side elevation view of half of the invention of FIG. 1.

FIG. 3B is an enlarged left side elevation view of the other half of the invention of FIG. 1.

FIG. 4A is an enlarged right side elevation view of half of the invention of FIG. 1.

FIG. 4B is an enlarged right side elevation view of the other half of the invention of FIG. 1.

FIG. 5 is an enlarged front elevation view thereof.

FIG. 6 is an enlarged rear elevation view thereof.

FIG. 7 is a top plan view thereof; and,

FIG. 8 is a bottom plan view thereof.

The stippling shown in the drawings represents a texture on the surface of the claimed design. The broken lines shown in FIG. 8 illustrate features of the article to which the design is applied that form no part of the claimed design.
